(No Model.)

F. P. CRAIG.
CULTIVATOR.

No. 408,589.

Patented Aug. 6, 1889.

UNITED STATES PATENT OFFICE.

FRANK P. CRAIG, OF HOLTON, KANSAS.

CULTIVATOR.

SPECIFICATION forming part of Letters Patent No. 408,589, dated August 6, 1889.

Application filed May 4, 1889. Serial No. 309,575. (No model.)

To all whom it may concern:

Be it known that I, FRANK P. CRAIG, a citizen of the United States, residing at Holton, in the county of Jackson and State of Kansas, have invented certain new and useful Improvements in Corn-Cultivators; and I do hereby declare the following to be a full, clear, and exact description of the invention, such as will enable others skilled in the art 10 to which it appertains to make and use the same.

The invention relates to improvements in corn-cultivators, being especially adapted to cultivate listed corn; and it consists in the 15 construction and novel combination of parts hereinafter described, illustrated in the accompanying drawings, and pointed out in the appended claims.

Figure 1 of the drawings represents a perspective view of a device embodying the invention. Fig. 2 represents a modification thereof in detail, and Fig. 3 represents a central longitudinal section through the lever-handle and sleeve.

25 Referring to the drawings by letter, A designates the main frame of the machine, consisting of the runners a , of ordinary construction and parallel to each other, and the transverse beams a' a'' , secured to the tops of the 30 runners, respectively, near the front and rear ends thereof. To the front beam a' is secured the tongue, of any desired construction.

a^3 is the driver's seat, resting on standards rising from the tops of the runners just in 35 front of the rear beam a^2 , as shown. The runners may, if desired, be adjusted nearer together or farther apart by means of openings in the transverse beams a' a'' and pins or bolts that pass through said openings into 40 registering openings in flanges on the runners.

a^4 a^4 are harrow-teeth that incline downward and rearward and pass through and are secured in series of openings (one or more in number) arranged in line in the beam a' , adjacent to the ends thereof. The beam a' is 45 longer than the beam a^2 and extends on each side equal distances farther out than the latter.

B B are bars perforated at each end and 50 engaging at said ends the adjacent end of S-shaped hooks b , the opposite ends of which

are engaged in openings b' , arranged in line along the facing edges of the beams a' a'' . The openings b' in the beams a'' are equal in number to the bars B; but there are half as 55 many again of said openings in the beam a' , so that the inclination of the bars B, which stand forward and outward from the beam a'' , can be changed by inserting the hooks b , connecting to the beam a' , into openings farther 60 inward or outward.

b^2 b^2 are harrow-teeth inclining downward and rearward and passing through and secured in series of aligned openings in the bars B.

65 C C are plow-points the standards of which pass upward through any one of the series of openings c near the ends of the beam a'' , and are engaged thereabove by the nuts c' , so that the said points can be adjusted outward and 70 inward.

D is a transverse shaft journaled in standards rising from the beam a'' near the ends thereof, and having one end bent at right angles to the outer side of one of said standards, 75 preferably the one on the right side.

E is a curved or semicircular rack rising from the beam a^2 to the outer side of the shaft D, and e is a lever-handle secured to and rising up from said portion and having a spring- 80 latch.

G are arms provided with the perforated or slotted heads g at their outer ends and the sleeves g' at their inner ends, which sleeves surround the shaft D and may be moved closer 85 together or farther apart thereon and then fixed in position by the set-screws g^2 , which pass through internally-threaded bosses on the sleeves.

g^3 is an opening at a suitable point in each 90 arm G, the series of openings g^4 in the head of said arm being concentric with said openings g^3 .

H H are plow beams or standards, having 95 their inner portions h straight and their outer portions about semicircular, to the ends of which outer portions are suitably secured the plow-points h' . The ends of the straight portions h are pivoted, by bolts or otherwise, to the corresponding openings g^3 of the arms G, 100 and they are provided with an opening that registers with any one of the corresponding

series of openings g^4 , so that by means of the openings g^4 and bolts or pins h^2 the beams H can be set at different angles on the arms G .

By means of the lever-handle, rack, detent-bar thereof, shaft D , and arms G the beams H and plow-points h' can be elevated, so that they will not touch the ground when it is not desired to operate them.

I is a shield bent longitudinally and centrally downward on each side and connected by the arms i to the runners, which arms are pivoted at their front ends upon the rear portions of the runners, as shown. The said shield prevents the soil from being thrown too far inward by the points h' . The shield is connected to the curved part of the runners by the chain K , the ends of which are engaged in openings in the highest parts of said curved portions, while its middle portion passes through a ring secured to the top of the shield.

If desired, the bars B may be detached and the machine operated without them.

In the modified form shown in Fig. 2 the harrow attachment has on the inner side the eyebolt b^3 , engaging on the rods L , secured to the side of the runner, so that the said attachment can be moved at this side up and down on said rods. This construction also serves as a hinge to enable the attachment to be tilted or lifted sidewise by means of the chain M , which leads to a point near the driver's seat, and thus allows the attachment to pass over stones or the trash to fall away from it.

The joints formed by the S-shaped hooks permit the removable bars to swing or twist laterally, so that the teeth b^2 can turn to one side, out of the way of obstructions.

Having described my invention, I claim—

1. In a corn-cultivator, the combination, 40 with the main frame composed of the runners and the transverse beams $a' a^2$, of the removable bars B , extending inward and rearward, provided with the harrow-teeth b^2 , and connected to the beams $a' a^2$ by flexible joints, so 45 that the said teeth can turn laterally out of the way of obstructions, substantially as specified.

2. In a corn-cultivator, the combination, with the shaft D and means, substantially as 50 described, for rotating the same to and holding it in a desired position, of the arms G , provided with the heads g , having the openings g^4 , having the openings g^3 at proper points, and provided on their inner ends with the 55 sleeves g' , the set-screws g^2 , to hold the sleeves in proper position on the shaft D , the plow-beams having in their straight portions h openings registering with the openings g^3 , and the pivotal pins or bolts h^2 , substantially as 60 specified.

3. In a corn-cultivator, the combination, with the main frame provided with the runners a , of the arms G , turning on the shaft D , the plow-beams H , vertically adjustable on 65 the arms G , the shield I , with its arms i pivoted on the rear ends of the runners, and the chain K , connecting the beams H and shield I , so that the latter will rise with the former, substantially as specified.

In testimony whereof I affix my signature in presence of two witnesses.

FRANK P. CRAIG.
